Arthur B. Leukens,
ATTORNEY

UNITED STATES PATENT OFFICE

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT

COIN CONTROLLED ACTUATING DEVICE

Application filed April 14, 1932. Serial No. 605,177.

My invention relates to devices the operations of which are controlled by means of falling coins and an object of my invention, among others, is the provision in a device 5 of this type of means for preventing fraudulent operation by means other than that of a coin.

One form of a device embodying my invention and in the construction and use of 10 which the objects herein set out, as well as others, may be attained is illustrated in the accompanying drawing, in which—

Figure 1 is an isometric view on enlarged scale of a portion of a coin controlled telephone apparatus embodying my improvement.

Figure 2 is a view, scale still further enlarged, illustrating the connection between the trip and the switch lever.

While my improved device is not limited 20 in its use to a mechanism of any particular type, yet, as it finds ready adaptation in the operation of coin controlled telephone apparatus I have shown it in the drawing herein in as embodied in such a mechanism. In apparatus of this type as heretofore constructed it has been possible to release certain members of the mechanism by jarring blows, or a succession of such blows applied 25 to the case containing the mechanism, and such fraudulent use has frequently been made use of to obtain service without the payment of a toll or fee therefor.

My improved device illustrated and described in the drawing herein is provided 35 with means whereby such fraudulent operation cannot take place, in such drawing the numeral 4 denoting a switch controlled frame, preferably of U-shape, pivotally 40 mounted on the upper end of a supporting post 5 rising from an electromagnet arrangement as commonly employed in apparatus of this sort, and for which reason a detailed description of such mechanism is omitted 45 herein. The frame 4 has a coin actuating finger 6 projecting from one side thereof into a slot 7 in a coin chute 8 having a hopper 9 into which a coin is directed in the operation of the device. A trip 10 in the form 50 of a projection from an upper side part of

the frame 4 forms a rest for a lever 11 comprising a portion of a switch actuating frame 12 pivotally mounted at the upper end of posts 13 projecting upwardly from the electromagnet arrangement heretofore 55 referred to. A switch actuating arm 14 projects downwardly from the frame 12 for the purpose of actuating the switch common to devices of this type.

All of the parts thus far described are of 60 old and well known construction and further and detailed description is therefore omitted herein. In applying my improvement to this device I form an inwardly curved edge 15 on the upper end of the trip, this curve being 65 preferably on the arc of a circle, the center of the arc being preferably on a line passing centrally through the trip 10, and as shown in Figure 2 of the drawing. I also provide a roller 16 pivotally mounted on a stud 17 projecting from a laterally bent end 18 of the lever 11, and as shown in Figure 1 of the drawing.

The mechanism is somewhat delicate in its construction, the weight of the coin on the finger 6 being sufficient to overcome the weight of the frame 4 thereby tipping the latter upwardly to release the trip 10 from the lever 11. The weight of the frame 4 is, however, sufficient to return the frame to its normal 75 position when the coin is released from the finger 6. Similarly while the resistance of the spring 19 is sufficient to retain the roller 16 in contact with the indented end 15 of the trip, this resistance is not sufficient to prevent the 80 trip from being readily disengaged from the lever 11 by the weight of a coin.

From this it will be seen that if the frame 4 be moved, as by a jar, to displace the roller 16 from the center of the indentation in either 90 direction, the roller will at once return to its mid-position and it will therefore be impossible, by a succession of jars, to dislodge the roller from the indented edge of the trip and thereby release the lever 11.

In accordance with the provisions of the patent statutes I have described the principles of operation of my invention, together with the device which I now consider to represent the best embodiment thereof, but I de- 100

sire to have it understood that the device shown is only illustrative, and that the invention may be carried out by other means and applied to uses other than those above set out.

I claim:

1. A coin actuated device including a movably mounted switch actuating member, a movably mounted frame including a coin actuated finger, and a trip having an indented edge comprising a rest at the end thereof for said switch actuating member.
2. A coin actuated device including a movably mounted switch actuating member pressed into contact with a trip, a movably mounted frame including a coin actuated finger, and a trip on said frame having an indented edge comprising a rest for said switch actuating member at the end thereof.
3. A coin actuated device including a movably mounted frame, a coin actuated finger projecting from said frame, a trip borne by said frame and having an indented edge, and a movably mounted switch actuating frame comprising a lever having its end supported in said indented edge of said trip.
4. A coin actuated device including a movably mounted switch actuating member having a laterally bent end, a movably mounted frame including a coin actuated finger and a trip having an indented edge, and a projection from said bent end resting in the indented edge of said trip.
5. A coin actuated device including a movably mounted switch actuating member having a laterally bent end, a roller rotatably mounted on said bent end, a movably mounted frame including a coin actuated finger, and a trip having an indented edge within which said roller is adapted to rest.

GEORGE A. LONG.
